FURNACE CONVEYER CHAIN

Charles R. Weiss, Indianapolis, Ind., assignor to
Link-Belt Company, a corporation of Illinois

Application November 17, 1936, Serial No. 111,328

19 Claims. (Cl. 198—168)

This invention relates to new and useful improvements in furnace conveyer chains.

It has been the practice for a considerable length of time to feed objects through heat treatment furnaces by means of one or more conveyer chains which operate in channels formed beneath the furnace floor. The conveyer chains have object feeding fingers which project into the heating chamber through narrow slots 10 formed in the furnace floor. This arrangement baffles the heat and protects the chain to a considerable extent. However, at times the chains acquire considerable heat from the high temperatures, and the chain parts lose their strength 15 and become warped or otherwise unsuited for further service.

With the advent of the longer type of furnaces, the chain problem has become more important, and in view of existing sprockets, channels, and 20 the like, radical changes in chain sizes cannot be made.

The primary object of this invention is to provide an improved form of high temperature furnace conveyer chain of the rolling type which 25 is less susceptible to bending, warping, and the like.

A still further important object of the invention is to provide a roller supported furnace conveyer chain in which no side crowding occurs 30 with the result that the rollers are always free to turn.

Other objects and advantages of the invention will be apparent during the course of the following description.

35 In the accompanying drawing forming a part of this specification and in which like numerals are employed to designate like parts throughout the same:

Figure 1 is a top plan view, partly broken 40 away, of a furnace conveyer chain assembly illustrating two links of the chain;

Figure 2 is a vertical sectional view taken on line 2—2 of Figure 1; and

Figure 3 is an exploded view of certain elements of the chain assembly.

Referring particularly to Figures 1 and 2, reference character 5 designates in its entirety a center link which can be of one-piece construction, as shown, or may be made from several 50 pieces, either construction including a pitch hole 6 at each end thereof. Each end of each pitch hole is formed with a concentric recess 1. Between the end portions of the center link 5, which are provided with the pitch holes 6, the 55 center link is provided with a pair of spaced, up-

standing attachment mountings 8 which are provided to have connected thereto object or material feeding fingers, not shown, which are adapted to extend into a furnace for feeding objects, or the like, through the heating zone of the 5 furnace.

Each end of the center link 5 is intended to have connected thereto a pair of side bars 9. One pair of these side bars is illustrated in Figure 1. Each side bar 9 has a pitch hole 10 formed in each of its end portions. Each side bar 9 has a boss 11 projecting laterally, inwardly from each end portion of the same and arranged concentrically with a pitch hole 10. Each end of each side bar 9 has projecting laterally, outwardly a pair of locking lugs 12 which are concentrically arranged with respect to the pitch hole 10. Each one of the side bars 9 is adapted to be arranged with each one of its end bosses 11 within a recess 7 at one end of a 20 center link 5. This assembly is clearly illustrated in section in Figures 1 and 2.

For the purpose of pivotally connecting the center link 5 to the illustrated pair of side bars 9, a chain pin 13 is arranged within the pitch 25 holes 6 and 10 of these elements. The chain pin 13 is of proper length to project beyond the outer side faces of both of the side bars 9. Each projecting end of the chain pin 13 has mounted thereon a hardened bearing bushing 14. Figures 2 and 3 illustrate each bushing 14 as having formed on one end thereof a pair of locking lugs 15. These locking lugs are adapted to be received between the adjacent end portions of the locking lug 12 formed on the associated side 35 bar 9. This locking connection between the bearing bushing 14 and its associated side bar 9 prevents relative angular movement between these elements. The opposite end portion of the bushing 14 is provided with apertures 16 to receive a retaining pin or cotter 17.

Each bearing bushing 14 is intended to have mounted thereon a supporting roller 18. For the purpose of retaining the roller against axial outward displacement from its bushing 14, a washer 45 19 is mounted upon the bushing 14 outwardly of the roller 18. This washer is notched at 20 to accommodate the retaining pin or cotter 17.

It will be noted that the retaining pin or cotter 17 functions to lock the bushing 14 to the 50 chain pin 13 to prevent either relative axial or relative angular movement between the chain pin and the bushing. It will also be recalled that the bushing has been described as being locked to its associated side bar 9 so as to pre- 55

vent relative angular movement between the bushing and side bar. The retaining pin or cotter 17 also functions to prevent rotation of the washer 19.

5 It will be appreciated that the combination of the recess 7 and boss 11 of the center link 5 and side bar 9, respectively, synchronized with the shear value of the chain pin 13, reduces bending moment on the pin, and consequently at elevated 10 temperatures the chain pin is less susceptible to bending. The described association of the side bar 9 with the bushing 14, the washer 19, and the retaining or cotter pin 17 prevents side crowding so that the roller is always free to turn and has 15 no tendency to bind.

It is to be understood that the form of this invention herewith shown and described is to be taken as a preferred example of the same and that various changes in the shape, size, and arrangement of parts may be resorted to without departing from the spirit of the invention or the scope of the subjoined claims.

Having thus described the invention, I claim:

1. In a furnace conveyer chain assembly, a center link having recesses at the ends of its pitch holes, side bars having bosses received in said recesses and having pitch holes, a chain pin journaled in the pitch holes of the side bars and center link and projecting beyond each side of the assembly, a bearing bushing mounted on each projecting end of the chain pin, a supporting roller journaled on each bushing, and means at the ends of the chain pin for retaining the rollers and bushings in place.

35 2. In a furnace conveyer chain assembly, a center link having recesses at the ends of its pitch holes, side bars having bosses received in said recesses, a chain pin connecting a pair of side bars to the center link and projecting beyond each side of the assembly, a bearing bushing 40 mounted on each projecting end of the chain pin, means for locking the bushings to the side bars to prevent angular movement therebetween, a supporting roller journaled on each bushing, and means for retaining the rollers in place.

45 3. In a furnace conveyer chain assembly, a center link having recesses at the ends of its pitch holes, side bars having bosses received in said recesses, a chain pin connecting a pair of side bars to the center link and projecting beyond each side of the assembly, a bearing bushing 50 mounted on each projecting end of the chain pin, means for locking the bushings to the chain pins to prevent movement therebetween, a supporting roller journaled on each bushing, and means for retaining the rollers in place.

60 4. In a furnace conveyer chain assembly, a center link having recesses at the ends of its pitch holes, side bars having bosses received in said recesses, a chain pin connecting a pair of side bars to the center link and projecting beyond each side of the assembly, a bearing bushing 65 mounted on each projecting end of the chain pin, means for locking the bushings to the side bars to prevent angular movement therebetween, means for locking the bushings to the chain pin to prevent movement therebetween, a supporting roller journaled on each bushing, and means for retaining the rollers in place.

70 5. In a furnace conveyer chain assembly, a center link having recesses at the ends of its pitch holes, side bars having bosses received in said recesses, a chain pin connecting a pair of side bars to the center link and projecting beyond each side of the assembly, a bearing bush-

ing mounted on each projecting end of the chain pin, interfitting lugs formed on the bushings and side bars to lock the same against relative angular movement, a supporting roller journaled on each bushing, and means for retaining the rollers 5 in place.

6. In a furnace conveyer chain assembly, a center link having recesses at the ends of its pitch holes, side bars having bosses received in said recesses, a chain pin connecting a pair of side bars to the center link and projecting beyond each side of the assembly, a bearing bushing 10 mounted on each projecting end of the chain pin, retaining pins for locking the bushings to the chain pin, a supporting roller journaled on each bushing, and means for retaining the rollers 15 in place.

7. In a furnace conveyer chain assembly, a center link having recesses at the ends of its pitch holes, side bars having bosses received in said recesses, a chain pin connecting a pair of side bars to the center link and projecting beyond each side of the assembly, a bearing bushing 20 mounted on each projecting end of the chain pin, interfitting lugs formed on the bushings and side bars to lock the same against relative angular movement, retaining pins for interlocking the bushings to the chain pin, a supporting roller journaled on each bushing, and means for retaining the rollers 25 in place.

8. In a furnace conveyer chain assembly, a center link having recesses at the ends of its pitch holes, side bars having bosses mounted in said recesses, a chain pin connecting a pair of side bars to the center link and projecting beyond each side of the assembly, a bearing bushing 30 mounted on each projecting end of the chain pin, interfitting lugs formed on the bushings and side bars to lock the same against relative angular movement, retaining pins for interlocking the bushings to the chain pin, a supporting roller journaled on each bushing, and means for retaining the rollers 35 in place.

9. In a conveyer chain assembly, a chain link side bar, a chain pin mounted in the pitch hole of said side bar and projecting beyond the outside face thereof, a hardened bearing bushing 45 mounted solely on the projecting portion of the chain pin and arranged entirely outwardly of the side bar, means for locking the end of the bushing and the side of the side bar which are adjacent to each other together to prevent relative angular movements, and a supporting roller 50 journaled on the bushing.

10. In a conveyer chain assembly, a chain link side bar, a chain pin mounted in the pitch hole of said side bar and projecting beyond one face of the side bar, a hardened bearing bushing 55 mounted on the projecting portion of the chain pin, means for locking the bushing to the chain pin to prevent relative axial and angular movement therebetween, and a supporting roller 60 journaled on the bushing.

11. In a furnace conveyer chain assembly, a center link and side bars having aligned pitch holes, a chain pin connecting a pair of side bars to the center link and projecting beyond each side of the assembly, a bearing bushing mounted entirely on each projecting end of the chain pin, 65 axially extending interfitting lugs formed on the bushings and side bars to lock the same against relative angular movement, a supporting roller journaled on each bushing, and means for retaining the rollers in place.

12. In a furnace conveyer chain assembly, a center link and side bars having aligned pitch 70 holes, a chain pin connecting a pair of side bars to the center link and projecting beyond each side of the assembly, a bearing bushing mounted entirely on each projecting end of the chain pin, 75 interfitting lugs formed on the bushings and side bars to lock the same against relative angular movement, a supporting roller journaled on each bushing, and means for retaining the rollers in place.

- holes, a chain pin connecting a pair of side bars to the center link and projecting beyond each side of the assembly, a bearing bushing mounted entirely on each projecting end of the chain, 5 axially extending interfitting lugs formed on the bushings and side bars to lock the same against relative angular movement, retaining pins for interlocking the bushings to the chain pin, a supporting roller journaled on each bushing, and 10 means for retaining the rollers in place.
13. In a furnace conveyer chain assembly, a center link and side bars having aligned pitch holes, a chain pin connecting a pair of side bars to the center link and projecting beyond each 15 side of the assembly, a bearing bushing mounted on each projecting end of the chain pin, a supporting roller journaled on each bushing, a retaining washer mounted outwardly of each roller, and means for locking the bushing, the 20 chain pin and the washer against relative angular movement.
14. In a furnace conveyer chain assembly, a center link having recesses at the ends of a pitch hole which is of uniform diameter between said 25 recesses, side bars having pitch holes of the same diameter as said link pitch holes and bosses received in said recesses, a chain pin rotatably fitting said center link and side bars pitch holes to be restrained against bending thereby and 30 projecting beyond each side of the assembly, a bearing bushing mounted on each projecting end of the chain pin, a supporting roller journaled on each bushing, and means at each extremity of the chain pin for maintaining the assembly.
15. In a furnace conveyer chain assembly, a chain link side bar, a chain pin mounted in the pitch hole of said side bar and projecting beyond one face thereof, a bearing bushing mounted entirely on the projecting portion of the chain pin 35 and laterally of the side bar, axially extending means for locking the end of the bushing adjacent the side bar to said side bar to prevent relative angular movement, and a supporting roller journaled on the bushing.
16. In a furnace conveyer chain assembly, a chain link side bar, a chain pin mounted in the 40
- pitch hole of said side bar and projecting beyond one face thereof, a bearing bushing mounted entirely on the projecting portion of the chain pin and laterally of the side bar, axially extending means for locking the end of the bushing adjacent the side bar to said side bar to prevent relative angular movement, a supporting roller journaled on the bushing, and means to lock the outer end of the bushing to the chain pin. 45
17. In a conveyer chain assembly, a chain link side bar, a chain pin mounted in the pitch hole of said side bar and projecting beyond one face thereof, a bearing bushing mounted entirely on the projecting portion of the chain pin, means for locking the end of the bushing adjacent the side bar to said side bar to prevent relative angular movement, a supporting roller journaled on the bushing, a retaining washer mounted on the outer end of the bushing, and means for locking the bushing, the chain pin and the washer together. 50
18. In a furnace conveyer chain assembly, a one-piece center link and side bars having aligned pitch holes of the same diameter, a chain pin extending through the pitch holes of said center link and side bars to pivotally connect said link and side bars and projecting beyond each side of the assembly, a bearing bushing mounted entirely on each projecting end of the chain pin, a supporting roller journaled on each bushing, and means positioned outwardly of the rollers for detachably retaining the rollers and the bushings in place. 55
19. In a conveyer chain assembly, the improvement which comprises a chain link side bar having a pitch hole and a locking lug projecting laterally of the bar adjacent the pitch hole, a bearing bushing arranged laterally of the side bar and having means at its inner end to interlock with said lug for preventing angular movement between the bar and bushing, a roller journaled on the bushing, and means for retaining the aforementioned elements assembled. 60

CHARLES R. WEISS.
